UNITED STATES PATENT OFFICE.

GILBRAITH STITT, OF SALTSBURG, PENNSYLVANIA.

CONVEYER.

No. 828,900.

Specification of Letters Patent.

Patented June 19, 1906.

Application filed January 8, 1906. Serial No. 294,411.

To all whom it may concern:

Be it known that I, GILBRAITH STITT, a citizen of the United States of America, residing at Saltsburg, in the county of Indiana and State of Pennsylvania, have invented certain new and useful Improvements in Conveyers, of which the following is a specification, reference being had therein to the accompanying drawings.

10 This invention relates to certain new and useful improvements in conveyers, and the invention relates more particularly to a conveyer adapted to be used in connection with the rolls of tin-mills, merchant-mills, and the like manufacturing-mills.

20 The primary object of my invention is the provision of novel means for transferring a piece of material or work from the passes of a pair of rolls to a place where the piece can be easily gripped and again passed through the same rolls.

25 My invention aims to provide a conveyer wherein novel means is employed for gripping a piece of work and conveying it to a desired point, and in this connection my improved conveyer is intended to be used in connection with tinning-mills, wherein sheets of tin, or, as it is known to the trade, a "pack" is passed through rolls a number of times, it 30 requiring a workman upon each side of the rolls to manipulate the pack as it passes between the rolls.

35 My invention aims to dispense with a workman upon one side of the rolls and to provide a conveyer to receive the piece as it passes through the rolls and convey it over the top of the rolls, where it may be gripped and again passed between the rolls. To this end I have devised a conveyer adapted to be 40 driven by the rolls in connection with which it is used, means having been devised to grip the pack and automatically release the same at a predetermined time. I have also provided means for adjusting the conveyer for different sizes of packs, and during the entire 45 operation of the conveyer it will not be necessary for a workman to give it his attention except when it is to be adjusted to receive larger or smaller packs.

50 With the above and other objects in view, which will more readily appear as the nature of the invention is better understood, the same consists in the novel construction, combination, and arrangement of parts, to be hereinafter more fully described and then 55 specifically pointed out in the claims, and, re-

ferring to the drawings accompanying this application, like numerals of reference designate corresponding parts throughout the several views, in which—

60 Figure 1 is a side elevation of my improved conveyer. Fig. 2 is a plan, partly broken away. Fig. 3 is an enlarged side elevation of a portion of the conveyer illustrating the gripping mechanism. Fig. 4 is a fragmentary 65 sectional view of one of the guides of the conveyer.

65 In the accompanying drawings I have illustrated two housings 1 1, between which are journaled rolls 2 and 3, said housings and rolls being of a conventional form, such as are generally used in tinning-mills. My invention resides in providing the housings upon one side of the rolls with outwardly-extending guideways 4 4, said guideways being 70 inclined upwardly, as illustrated in Fig. 1 of the drawings, and having their outer ends supported by legs 5 5, which are suitably braced, as at 6, while the inner ends of said guideways are secured to the edges of the 75 housings 1 1, as at 7. The guideways are further braced by angularly-disposed bars 8 8, which are secured to the guideways, as at 80 9 9, and to the housings 1 and legs 5, as at 85 10 10.

85 Each guideway consists of two strips 11 11, and slidably mounted upon said guideways is a plate 12, the ends of said plate being held in engagement with the guideways by bolts and nuts 14, which extend between the 90 strips 11 11 of each guideway. The plate 12 is provided with outwardly-extending portions 15 15, these portions forming a foundation for the gripping mechanism 16 of my improved conveyer. Upon the plate 12 are 95 mounted two brackets 17 17, in which is mounted a pin 18. Journaled upon the pin 18 is a curved gripping-head 19, the lower end of said gripping-head extending into a slot 20, formed in the portion 15 of the plate 100 12. Pivotaly mounted upon the plate 12 between lugs 21 21 is a curved chain-grip 22, carrying a hook-shaped member 23, the object of which will be presently described. The chain-grip 22 is pivotally connected by 105 a link 24 with the lower end of the grip-head 19, said link extending between the brackets 17 17 into the slot 20 of the plate 12.

110 The angularly-disposed bars 8 8 adjacent to the housings are provided with bearings 25 25, in which a shaft 26 is journaled. The legs 5 5 at the outer end of the conveyer are

provided with adjustable brackets 27 27, in which a shaft 28 is journaled. Upon the shafts 26 and 28 are mounted sprocket-wheels 29 and 30, respectively, and over said wheels is adapted to pass a sprocket-chain 31. Upon the end of the shaft 26 is mounted a sprocket-wheel 32, over which passes a sprocket-chain 33, that engages a sprocket-wheel 34, mounted upon the neck 35 of the roll 3.

Slidably mounted upon the guideways 4 4 is a cross-head 36, said cross-head being slidably connected to the guideways 4 4 by bolts and nuts 37 37, similar to the bolts and nuts 14 of the plate 12. The cross-head is provided with upwardly-extending prongs 38 38 and with a depending strap or stirrup 39. Connected to the strap or stirrup 39 is a cable 40, which passes over a pulley 41, journaled in a bracket 42, carried by a transverse bar 43, secured to the housings 1 1. The lower end of the cable extends into the housing-pit 44 and is provided with a weight 45, whereby the cross-head 36 will be normally held in engagement with stop-blocks 46 46, carried by the outermost strips 11 11 of the guideways 4 4.

Adjustably mounted upon the guideways 4 4 by bolts and nuts 47 47 is a transverse bar 48, said bar being employed to limit the rearward movement of the head 36, the object of which will be presently described.

The housings 1 1 are provided with inwardly-extending brackets 49 49, and secured to said brackets are outwardly-extending guide-rails 50 50, said rails being provided with hinged members 51 51 and with a transverse guide-roller 52. The hinged members are adapted to lie in engagement with the guideways 4 4, as clearly illustrated in Fig. 1 of the drawings, and the use of these hinged members will be presently described.

The housings 1 1 adjacent to the pass between the rolls 2 and 3 are provided with a transverse bar 53, carrying guide-plates 54 54, which extend inwardly in close proximity to the pass between the rolls 2 and 3.

The lower face of the plate 12 is provided with a pierced lug 55, and connected to said lug is a cable 56, which passes over a pulley 57, journaled in the bracket 41, said cable extending into the pit 44 of the housings and having a weight 58 upon its lower end.

Operation: The normal position of the various parts of my improved conveyer is shown in the accompanying drawings, and I will assume that a pack is entering the pass between the rolls 2 and 3 from the direction indicated by the arrow A of Fig. 2 of the drawings. As the forward end of the pack rides upon the outwardly-extending portion 15 of the plate 12 the pack strikes the depending end of the gripping-head 19, forcing it forward and causing the rear end of the gripping-head to impinge the pack upon the

plate 12. The movement of the grip-head in engaging the pack causes the chain-grip 22 to descend through the medium of the link 24, and the end of the chain-grip engages in the chain 31, which will carry the plate 12 upwardly upon the guideways 4 4. As the plate 12 moves upwardly it strikes the cross-head 36, and the cross-head ascends upon the guideways, together with the plate 12, until the bar 48 is reached, which limits its movement, said bar also serving to release the chain-grip 22 by striking the hook-shaped member 23 of said grip. After the release of the chain-grip the plate 12 is allowed to descend to its normal position, together with the cross-head 36, this being accomplished through the medium of the weights 45 and 48, suspended in the pit 44 of the housings. As the plate 12 and the cross-head 36 ascend the pack passes beneath the hinged members 51 51, and when the plate 12 and the cross-head 36 descend the rear end of the pack travels upwardly upon the hinged members 51 51, upon the roller 52, and upon the rails 50 50. The plate 12 is adapted to pass beneath the hinged members 51 and descend to its normal position in close proximity to the pass between the rolls 2 and 3, the extremities of the hinged members 51 51 being slightly upturned, so that while the pack will travel upwardly on these members the plate 12, which has its front edge beveled, as shown in Fig. 1, will pass beneath the same, while the cross-head 36 will be retained by the stop-blocks 46 46. The gripping mechanism 100 16, having assumed its normal position, is in condition to grip another pack passed through the rolls 2 and 3, but may grip the pack again which has been passed over the top of the roll 2, said pack being received by 105 a workman and again fed between the rolls 2 and 3. The prongs 38 38 upon the cross-head 36 are employed for bracing a pack during its upward movement upon the rails 50 50, and the plates 54 54 are adapted to guide the pack from the pass between the rolls 2 and 3 to the plate 12. In case a very long pack is passing through the rolls the stop-blocks 46 46 are adjusted in order that the pack will not be forced too far from the roll 2, 110 and the transverse bar 48 is also adjusted to permit of the cross-head moving sufficiently to accommodate the entire pack upon the guideways 4 4 between the bar and the hinged member 51 51.

From the foregoing it will be observed that I have devised novel means for manipulating pieces of material passed between rolls where it is desired to again repass the material, thus dispensing with labor heretofore employed to 115 accomplish this result.

I do not care to confine myself particularly to a tin-mill, as the same may be readily employed in merchant-mills and rolling-mills, where a number of passes are employed for 120 130

giving the piece of material the proper reduction.

Such changes in the construction and operation of my improved conveyer as are permissible by the appended claims may be resorted to without departing from the spirit and scope of the invention.

What I claim, and desire to secure by Letters Patent, is—

- 10 1. In a conveyer, the combination with a housing of rolls, of angularly-disposed guideways, a plate slidably mounted upon said guideways, a cross-head slidably mounted upon said guideways, rails supported by said housing, hinged members carried by said rails and resting upon said guideways, a gripping mechanism carried by said plate and adapted to be actuated by a pack passing between said rolls, means engaged by said gripping mechanism to convey said plate, said pack and said cross-head upon said guideways, means to release said gripping mechanism, and means to return said plate and said cross-head to their normal position, substantially as described.
- 15 2. In a conveyer, the combination with a housing of rolls, of angularly-disposed guideways, a traveling chain mounted between said guideways, a plate mounted upon said guideways, gripping mechanism carried by said plate and adapted to be actuated by a pack passing between said rolls, to engage said pack and grip said chain, rails carried by said housing, hinged members carried by said rails and resting upon said guideways, a cross-head slidably mounted upon said guideways, and adapted to be moved by said plate, means to release said gripping mechanism, means to return said plate and said cross-head to their normal position, means to operate said chain, and means to support said guideways, substantially as described.
- 20 3. In a conveyer, the combination with the housing of rolls, of guideways, a plate slidably mounted upon said guideways, a cross-head mounted upon said guideways and adapted to be moved by said plate, a gripping mech-

anism carried by said plate and actuated by a pack passing between said rolls, rails carried by said housing and resting upon said guideway, means to move said plate upon said guideway, means to return said plate and said cross-head to their normal position, and means to support said guideway, substantially as described.

4. In a conveyer, the combination with a housing of rolls, guideways supported adjacent to said housing, a plate slidably mounted upon said guideways, a cross-head slidably mounted upon said guideways, means to move said plate and said cross-head, means carried by said plate to grip a pack passing through said rolls, means to return said plate and said cross-head to their normal position, and means to convey said gripped pack over said rolls, substantially as described.

5. In a conveyer, the combination with rolls, guideways mounted adjacent to said rolls, gripping mechanism slidably mounted upon said guideways, said gripping mechanism embodying means to grip a pack, means to move said gripping mechanism upon said guideways, means to release said gripping mechanism, means to convey said pack over said rolls, and means to return said gripping mechanism to its normal position, substantially as described.

6. In a conveyer, the combination with rolls, of guideways, means to convey a pack upon said guideways, means to release said pack, and means to guide said pack over said rolls, substantially as described.

7. The combination with rolls, of a gripping mechanism adapted to grip a pack, means to move said gripping mechanism, means to release said mechanism, and means to convey said pack over said rolls, substantially as described.

In testimony whereof I affix my signature in the presence of two witnesses.

GILBRAITH STITT.
